SNOWMOBILE ENGINE COWLING

Thomas Scott, Valcourt, Quebec, Canada, assignor to
Bombardier Limited, Valcourt, Quebec, Canada

Filed May 10, 1972, Ser. No. 252,163

Claims priority, application Canada Apr. 5, 1972

Term of patent 14 years

Int. Cl. D12—14

U.S. Cl. D14—24

FIG. 1 is a perspective view from the front and one side showing a snowmobile engine cowling;

FIGS. 2, 3 and 4 are respectively side front and rear elevations of the cowling; and

FIG. 5 is a plan view.

I claim:

The ornamental design for a snowmobile engine cowling, as shown.
